(57) **CLAIM**

The ornamental design for handle for stabilizing hand-held ratchet wrench, as shown and described.

DESCRIPTION

FIG. 1 is a perspective view of handle for stabilizing hand-held ratchet wrench showing my design;

FIG. 2 is a front elevation view thereof, the rear elevation view being a mirror image;

FIG. 3 is a left side elevation view thereof, the right side elevation view being a mirror image;

FIG. 4 is a top plan view thereof; and,

FIG. 5 is a perspective view thereof, connected to a hand-held ratchet wrench.

The broken line showing of a hand-held ratchet wrench in FIG. 5 of the drawings is for illustrative purposes only and forms no part of the claimed design.

The bottom surface of the article not shown in the drawing or described in the specification forms no part of the claimed design.
